POWER CASE-SHIFT MECHANISM

Harry C. Yaeger, West Hartford, Conn., assignor to Underwood Corporation, New York, N. Y., a corporation of Delaware

Application February 10, 1953, Serial No. 336,691

6 Claims. (Cl. 197—74)

This invention relates to typewriting machines and more particularly to case-shifting mechanism for such machines. The subject matter is a continuation-in-part of my application Serial No. 258,853, filed November 29, 1951, now Patent No. 2,681,720, issued June 22, 1954, as a division of application Serial No. 199,306, filed December 5, 1950, now Patent No. 2,703,641, issued March 8, 1955.

In most typewriting machines the type-bearing instrumentalities are case-shiftable relatively to paper supporting means, in order to condition the machine for typing by different case types. Regardless of whether such relative shift is accomplished by a shift of the paper supporting means or a shift of the type-bearing instrumentalities, there exists the problem of quickly setting in motion and arresting a considerable case-shift mass in an interval of time which must be very short for speedy operation of the machine. Furthermore, it is most desirable to effect the case-shifts with a minimum of attendant shock and noise.

It is therefore an object of the invention to provide an efficient, quickly, smoothly and quietly operating case-shifting mechanism.

It is a further object of the invention to provide a power-operated, case-shift mechanism which will operate with a minimum of applied motor power, smoothly and substantially noiselessly.

Also an object of the invention is to provide in efficient cooperation with a case-shift means which may include power means, an efficient case-shift cushioning device which during cushioning action stores a substantial amount of energy, and which beneficially applies such stored energy to aid a succeeding motor-operated case-shift operation.

Other objects and features of the invention will be in part obvious and in part pointed out particularly as the following description of a preferred embodiment of the invention proceeds.

The invention is illustrated in association with a pressure printing typing mechanism which is the subject of the aforementioned patent application Serial No. 199,306, and which embodies a pivotally case-shiftable type carrier system.

Turning now specifically to the drawings:

Figure 1 is a fractional right-hand side elevation of a typewriting machine showing the power case-shifting mechanism of the invention in its normal, lower case condition, and idle.

Figure 2 is a fractional side elevation similar to Figure 1, but the power case-shifting mechanism is shown in an upper case condition.

Figure 3 illustrates two parts of a spring supporting device.

Referring now more particularly to Figure 1, the machine to which the invention is applied comprises two main side plates or walls 18. Between these side walls there is case-shiftably supported on pivot studs 34 provided on the opposite machine walls 18, a body or unit

2

30 having thereon a system of type carriers 40. The individual type carriers 40 are selectively operable under key control to type against a usual work-sheet supporting platen 24. The case-shiftable body 30 includes adjacent the inside of each machine wall 18 a side plate 33, these plates being connected by various members including one numbered 188.

The said case-shift body 30 is shown in its normal, lower case position in Figure 1. In this position an arm 181 of each side plate 33 of the case-shiftable body 30 abuts an eccentrically adjustable normal case stop 182, each such stop being carried on the adjacent side wall 18 of the machine. In the stated normal case position of the case-shift body 30, the type carriers 40 are selectively operable to type by either of two lower case types 51, as indicated by dot-and-dash lines.

In Figure 2 the case-shift body or unit 30 is shown in upper, that is, in capital case position. The arms 181 abut each upwardly against a capital case stop 183 which is similar to and adjustably supported in the same manner as the normal stop 182. In the stated capital case position of the body the type carriers 40 are selectively operable to type by either one of two upper case types 51c, as indicated by two dot-and-dash lines in Figure 2.

For moving the case-shift body 30 to and from case-shifted position there is provided a noiselessly operating power mechanism which in some respects is similar to a mechanism disclosed in the U. S. Patent to Helmond, No. 2,275,759, dated March 10, 1942. This power mechanism includes a normally quiescent eccentric 195 having associated therewith, by means of a ring of balls 197, a connecting rod 196, said balls being accommodated in opposite ball races provided in the eccentric 195 and the connecting rod 196, whereby said eccentric is turnable with a minimum of friction in the connecting rod and the latter is retained on the eccentric. The connecting rod has a pivotal connection with a rocker 198 that is pivotally carried at 200 on the left side wall 18 of the machine frame. The rocker has adjustable abutments 201 straddling a pin 202 extending laterally from a down-reaching portion of the left end plate 33 of the case-shift body 30. The pin 202 extends through a clearance hole in said side wall 33. The eccentric 195 is turnably mounted on a shaft 203, the latter of which is constantly rotating when the machine is in use and carries fast on the outer end thereof, adjacent the eccentric 195, a toothed rotor or clutch wheel 204. Provision is made to couple the eccentric 195 to said toothed wheel 204 to be turned thereby a half turn upon downward operation of a shift key 205 and to be turned another half turn upon restoration of such shift key. A clutch pawl 206 pivotally carried on the eccentric 195 is normally held free of the toothed wheel 204 by a control dog 207 that normally engages an outreaching nose of the pawl. A compression spring 208 carried in a portion of the eccentric engages a tail of the pawl 206 and thereby tends to swing the pawl inwardly into coupled association with the wheel 204. Diametrically opposite to the control dog 207 there is another control dog 210 which when the case-shift key is in normal position is clear of the orbit of the pawl 206. The two dogs 207, 210 are each pivotally carried as at 212 on a bracket 211. A link 213 connects the two dogs. The case-shift key 205 is borne on a lever 209 fast on a shaft 214 and when said key is operated an arm 215 on the left end of the shaft 214 draws a link 216 forwardly. The latter has a pivotal connection with the dog 210 and upon operation of the shift key 205 will swing the dog 210 into the orbit of the out-reaching nose of the pawl 206. At the same time due to the link 213 which connects the two dogs, the dog 207 will swing clear of the nose of the pawl 206, wherefore the eccentric 195 becomes coupled to the toothed wheel 204 to turn therewith. At the end of a half turn the

connecting rod 196 will be in the rearward position seen in Figure 2, and through operation of the rocker 198 will have displaced the case-shift body 30 to the upper case position. The half turn of the eccentric is terminated by engagement of the outreaching nose of the pawl 206 with the hooked end of the dog 210, such engagement resulting in a limited outswinging movement of the pawl to free the latter from the toothed wheel 204 as shown in Figure 2. At the release of the case-shift key 205 the dogs 207, 210, under the tension of a spring 217 associated with the link 216, return to their normal positions seen in Figure 1. Consequently the pawl 206 will reengage the toothed wheel 204 for a second half turn of the eccentric 195, such half turn being terminated as the pawl 206 is intercepted by the dog 207 and swung clear of the wheel 204. During such second half turn the connecting rod 196 is driven forwardly by the eccentric and through restoration of the rocker 198 will restore the case-shift body 30 to the normal case position seen in Figure 1. The motion imparted to the connecting rod 196 is of harmonic characteristic and, as will become evident hereinafter, a strong resilient means associated with the heavy case-shift body 30 and strained in the half part downward movement exclusive of a first part downward movement is an important cooperative factor in a cooperative organization whereby said heavy case-shift body is smoothly picked up in each case position, smoothly moved, and deposited in the other case position with the least attendant shock and noise. Also the disengagement of the pawl 206 from the wheel 204, and the arrest of the eccentric 195 is achieved without shock and noise, but this feature is the subject matter of application Serial No. 258,853, hereinbefore noted. Briefly stated, the dogs 207, 210 yield slightly when they are engaged by the clutch pawl 206, such yield being afforded by leaf springs 218 of gooseneck form. Moreover, as shown in reference to the dog 207, the gooseneck spring 218 may be backed up by a relatively solid abutment 220 which is normally spaced slightly from said spring. The opposite range of movement of the dogs is controlled by two stop pins 219. Due to the resiliency of the gooseneck spring 218, the eccentric 195 has a tendency to rebound in reverse direction as the pawl 206 is intercepted at each half turn of the eccentric. To control this rebounding tendency, the eccentric 195 carries fast thereon a two-lobe member 223 with which there cooperates a spring pressed pawl 224.

While the machine is in use, the shaft 203 is preferably continuously motor-driven at a desired case-shift speed.

The case-shift body 30, along with all the mechanism thereon, represents an appreciable mass, and because it must be moved from one case position to the other in a very short interval of time, there arises the problem of attendant shock, noise and rebound. It is old and well known in the art to provide spring means substantially to counterbalance the mass of a case-shift body, but in a downward shift the acceleration of the body due to gravitation soon assumes such magnitude that the force of momentum of the body will over-power decisively ordinary counterbalancing spring means. Resultingly, the substantial case shift mass under the conditions stated cannot be controlled and brought to rest as smoothly and quietly as desired. Moreover, in the first half of the upward shift the substantial mass of the body is a strong opposing factor conducive to harshness of operation and strain. Merely to provide a counterbalancing spring is therefore not a solution toward providing a most efficient, smooth and shockless case-shift operation.

Now with more specific reference to the power operating eccentric 195 shown in the drawings, it is to be noted that the clutch 204, 206 therefor is one-way driving, for ease, speed and reliability of engagement, and that the eccentric 195 under a condition of permitted excessive gravitational influence of the case-shift body, through a pull on the connecting rod 196, will be driven and accelerated to exceed the speed of the toothed driving wheel

204. That is to say, the motion of the eccentric 195 will cease to be controlled by the speed of operation of the toothed drive wheel 204 and will have a run-away characteristic. Obviously, under the stated condition there cannot prevail a smooth and controlled movement of the heavy case-shift body, conducive to smooth, shockless and noiseless case-shift operation.

According to the invention the gravitational acceleration of the case-shift body, after an initial, relatively free movement has been allowed to take place, is thereafter counteracted by the straining of a strong resilient means. In the embodiment of the invention shown, the resilient means is in the form of a strong compression spring 236 that is strained over the second half of the downward movement of the case-shift body 30. The opposition to movement so provided for prevents a run-away gravitational movement of the case-shift body 30 in the second half of the downward shift, while on the other hand initially there prevails a low resistance to movement to allow the case-shift mass to get smoothly under way. Moreover, the strong spring 236 in being strained, stores a significant amount of energy as the case-shift body 30 is power-driven to its lower position at harmonic motion characteristic by the eccentric 195.

Subsequently when the eccentric 195 thereafter is turned to shift the body 30 to its upper position, the energy stored in the strong spring 236 asserts itself to aid the movement of the body and relieve operational strain, it being noted however that the eccentric 195 needs to move first appreciably from dead center position for the energy storing spring 236 to exert its beneficial action to lessen the resistance to rotation of the eccentric 195.

In the specific embodiment of the invention illustrated, the said strong spring 236 is a compression spring and is part of a spring unit or device 226 which may embody also a relatively weak compression spring 235. There may be a spring device 226 on each side of the machine but according to the preferred embodiment of the invention shown, there is only one on the side of the power-operable case-shift rocker 198. The stated spring device 226 comprises an upper and a lower link member 227, 228 respectively, having forked portions 230, see Figure 3, interfitting one another to allow their distention lengthwise. The upper link member 227 has a pivotal joint with the overlying arm 181 of the case-shift body as at 231, while the lower link 228 has a forked lower end fitting in a notched bottom of an opening 232 in the side plate 18 of the machine. Each of the two links 227, 228 is shouldered as at 233 for spring seating elements 234 to abut thereagainst. The relatively light compression spring 235 is loosely accommodated on the link members 227, 228, and interposed in compression between the two seats 234 exerting a light upward force on the case-shift body 30 substantially balancing merely its aggregate weight. The spring device 226 embodies the stronger compression spring 236 between the two spring seats 234 in a loosely surrounding relation to the lighter spring 235. The heavy spring 236 with the case-shift body residing in upper position is shorter than the space between the two spring seats 234 to an extent so that such spring commences to be strained approximately when one-half of the downward movement of the case-shift body 30 from upper to lower position has taken place. By that time the case shift body has assumed high speed and the gravitational influence thereon vigorously tends to increase its speed. However, it will be evident that in the second half part of the downward movement of the body 30 the heavy spring 236 opposes strongly the gravitational run-away tendency of the body, causing it to move at a smooth controlled pace and preventing it from driving the eccentric 195 at a speed in excess of the power-driven toothed wheel 204. The downward shift of the body 30 is thus accomplished with smoothness and ease. At the same time, in being strained, the heavy spring 236 stores an important amount of energy which in the opera-

tion of the eccentric 195 to effect an upward shift of the body 30, after an initial movement from dead center position, asserts itself effectively and beneficially to aid the upward shift of the body and make the rotation of the eccentric easier, thereby lightening the load on the motor and generally contributing to smoother operation. It will be noted that the eccentric 195 forces the case-shift body 30 to normal case, lower position against the resistance of the heavy spring 236 which is conducive to snubbing such movement. At the end of such movement 10 the case-shift body 30 is held stationary because the eccentric 195 reaches and is arrested in dead center position, and because the check pawl 224 in cooperation with the load member 223 prevents backward rotation of the eccentric 195.

Since the lighter spring 235 merely balances substantially the weight of the case-shift body 30 inclusive of the mechanism supported thereon, it follows that in a power-operated case-shift movement of said body to upper, capital case position, the eccentric 195 works with great ease. The body upon arrival in upper case position is held thereat due to the dead center position reached by the eccentric 195, see Figure 2. When the eccentric 195 receives a half turn to case-shift the body 30 down to the normal case position seen in Figure 1, it follows that an appreciable first-part movement of the case-shift body 30 is against very little resistance.

Due to the structure cooperative hereinabove described the motor power can be kept to a minimum and the case-shift movement in either direction gets under way and is accomplished against smoother effective resistance, reducing shock and noise. This in turn makes feasible a higher speed of power operation for the eccentric 195 than otherwise would be practically feasible for the same case-shift mass.

Obviously the eccentric stops 182, 183 associated with the arms 181 of the case-shift body 30 are adjusted for proper correlation so that when the eccentric 195 is in either of its opposite dead center positions the arms 181 will firmly engage the appropriate eccentrics.

It is understood that the invention may take other forms than that shown and that for example a single spring may be provided having substantially the combined characteristic of the two springs 235, 236.

Obviously also the invention is not restricted to case-shifting a pivotally mounted case-shift body, nor to case-shifting a type system instead of a carriage. It is also understood that the case-shift operating mechanism may take other forms than that shown. In general, variations of the structure may be resorted to within the scope of the invention and portions of the improvement may be used without others.

What is claimed is:

1. In a typewriting machine having a case-shift body mounted for downward and upward case-shifts between an upper and a lower position, flexibly strainable means arranged to oppose downward shift of said body, comprising relatively easily flexible spring-turns approximately counterbalancing the weight of the body to resist moderately the body in a first part downward shift, and comprising also relatively much harder strainable spring-turns to resist heavily the body substantially throughout the second half of the downward shift but exclusive of an appreciable first part of the downward shift, whereby said harder strainable spring-turns store a significant amount of energy in the downward shift of the body, and harmonic motion means controllable to shift said body from either of said positions to the other and to hold it there, said harmonic motion means, resultant to shifting the body to lower position, being effective to hold said harder strainable spring-turns against effectively acting upwardly on said body, and consequential to starting the shift of said body from said lower to said upper position enabling said harder strainable spring-turns to exert energy stored therein to assist effectively and strongly thereafter

the upward shift of the body substantially not less than half-way toward the upper position.

2. In a typewriting machine having a case-shift body mounted for downward and upward case-shifts between an upper and a lower position, abutment means directly associated with said body to stop it oppositely in its shifts to its upper and its lower position, flexibly strainable means arranged to oppose downward shift of said body, comprising relatively easily flexible spring-turns approximately counterbalancing the weight of the body to resist moderately the body in a first part downward shift, and comprising also relatively much harder strainable spring-turns to resist heavily the body substantially throughout the second half of the downward shift, but exclusive of an appreciable first part of the downward shift, whereby said harder strainable spring-turns store a significant amount of energy in the downward shift of the body, and harmonic motion power means to shift said body from either of said positions to the other against said abutment means and to hold it there, said harder strainable spring-turns, consequential to initial movement of said harmonic motion power means in effecting the shift of the body from said lower to said upper position, becoming automatically enabled to exert beneficially the energy stored therein to assist effectively and strongly thereafter the upward shift of the body substantially not less than half-way toward the upper position.

3. In a typewriter having a case-shift body mounted for movement between an upper and a lower case position, spring means associated with said body and of a character to counterbalance substantially said body when it is stationed in upper position and in a second half part downward movement exclusive of a first part downward movement being strained to resist heavily the downward movement of the body and storing energy in doing so, means to shift said body from each one to the other of the said two positions and including a harmonic motion device to drive said body to and from lower position with harmonic motion action, and in driving it to lower position holding it there, said spring means consequential to initial movement of said harmonic motion device to effect the shift of the body from said lower to said upper position becoming automatically enabled to exert beneficially the energy stored therein to assist effectively and strongly the upward shift of the body substantially not less than half-way toward the upper position.

4. In a typewriter having a case-shift body mounted for movement between an upper and a lower position, strong flexible means associated with said body to resist the movement of said body strongly throughout the second half of its downward movement but having no movement-resisting action on the body during an appreciable first-part downward movement of such body, and power means controllable to drive said body oppositely from each of the said positions to the other and hold it there, including, a motor-operable rotor, a harmonic motion device and a one-way clutch by which said rotor is capable to drive said harmonic motion device, said harmonic motion device adapted to drive said body to said lower position ending in harmonic motion action thereon and reversely adapted to drive it from said lower position with harmonic motion action, said body in being driven to said lower position straining said strong flexible means and said harmonic motion means after driving said body to said lower position being effective to hold it there against the upward urge which said strained flexible means exerts on said body, the said harmonic motion device, consequential to driving said body an initial part upwardly, enabling said strong flexible means to exert beneficially the energy stored therein to assist strongly the upward drive of said body by said harmonic motion device toward said upper position and not less than half-way toward such upper position.

5. In a typewriter having a case-shift body mounted for movement between an upper and a lower position,

7
spring means associated with said body and of a character to counterbalance substantially said body when it is stationed in said upper position, and in a second half part downward movement exclusive of a first part downward movement, being strained to resist heavily the downward movement of said body and storing energy in doing so, and means to move said body oppositely from either of said positions to the other, including, a motor-driven rotor, a displacement element connectable for operation by said rotor to operate said body from said upper to said lower position and having provision to move said body at rapidly diminishing speed throughout the lower half of its downward movement, and a one-way drive clutch controllable to connect said element for rotation by said rotor to effect movement of said body from said upper to said lower position and also controllable to effect movement of said body from said lower to said upper position, said spring means resisting strongly the body in its second half part downward movement and thereby preventing said body from exceeding the rate of speed at which the rotor is able to drive the body through said displacement element by said one-way drive clutch, the energy stored in said spring means after the movement of said body to said lower position assisting strongly the upward movement of said body about half-way toward said upper position.

6. In a typewriting machine having a case-shift body mounted for opposite case-shift movement on a frame to an upper and a lower position, a relatively light com-

10
15
20
25
pressive spring, a relatively strong compressive spring, the latter having an inside diameter larger than the outside diameter of the former and substantially coaxially arranged to surround the former, spring seating means to accommodate said light spring in compression between said frame and said case-shift body to exert always a lifting force on said body, means oppositely on the frame and said body to compress said strong spring in the movement of said body from its upper to its lower position only after a first part of such movement has taken place and substantially throughout the second half movement, whereby a significant amount of energy is stored in said strong spring in a second half movement of the body to said lower position, and means to move said body from either of said positions to the other and upon movement of said body to either of said positions being instrumental to hold it there, said body moving means upon effecting initial movement of said body toward said upper position being instrumental to cause said strong spring to aid strongly the movement of the body substantially half-way toward its upper position.
